WILLIAM H. PERKINS AND CARL A. LINDGREN, OF HATHORNE, MASSACHUSETTS.

AUTOMATIC LAUNDRY-VALVE.

1,103,828.

Specification of Letters Patent. Patented July 14, 1914.

Application filed January 26, 1914. Serial No. 814,389.

To all whom it may concern:

Be it known that we, WILLIAM H. PERKINS and CARL A. LINDGREN, citizens of the United States, and residents of Hathorne, in the county of Essex and State of Massachusetts, have invented a new and Improved Automatic Laundry-Valve, of which the following is a full, clear, and exact description.

10 This invention relates to laundry appliances and has particular reference to means for controlling the admission of water into a laundry machine.

15 Among the objects of the invention, more definitely stated, is to provide a valve mechanism of peculiar construction, whereby the flow of water into the washing machine may be controlled automatically in accordance with the depth of water therein.

20 A further object of the invention is to provide a peculiar means for determining the temperature of the water to be delivered into the machine.

25 The foregoing and other objects of the invention will hereinafter be more fully described and claimed and illustrated in the drawings forming a part of this specification in which like characters of reference indicate corresponding parts in all the views, and in which—

30 Figure 1 is a side elevation of a valve casing made in accordance with a preferred form of the invention; Fig. 2 is a horizontal section of the same substantially on the line 2—2 of Fig. 1; Fig. 3 is a transverse section on the line 3—3 of Fig. 2, but indicating the movable valves removed; Fig. 4 is a view of the movable valve casing; Fig. 5 is a transverse section of the same on the line 5—5; Fig. 6 is a view on the line 6—6 of Fig. 2; and Fig. 7 is an end elevation of a washing machine showing our improvement attached thereto.

35 The several parts of the device may be made of any suitable materials, and the relative sizes and proportions, as well as the general design of the mechanism, may be varied to a considerable extent without departing from the spirit of the invention 40 hereinafter more fully set forth and specifically claimed.

45 At 10 we show a machine of any suitable character into which water is to be delivered through a pipe 11 and from which the 50 water may be drawn through an outlet pipe 12. 13 indicates a valve casing adapted to

receive cold water through a pipe 14 and hot water through a pipe 15, said casing having means within it to control the supply of water with respect to its being hot or cold, and deliver the same into and through the inlet pipe 11.

55 The valve casing 13, shown best in Fig. 2, is of peculiar construction and includes a stationary cylindrical shell 16 having two circular series of inlet ports 17 surrounding the same. Said series are spaced from each other on opposite sides of the plane coinciding with the axes of the hot and cold water pipes 14 and 15. The water from each of these pipes admitted into the casing is received upon the outer cylindrical surface of the shell 16 and is conveyed along the outer surface of the shell within an annular chamber 18 in communication with the set of ports 17 pertaining thereto; that is to say, the water from the pipe 15 flows through the shell 16 in one of the series of ports 17, and the cold water flows through its shell 18 to and through the other series 60 of ports 17 into the interior of the shell 16.

65 At 19 we show a movable or slidable valve adapted to be reciprocated within the shell 16 by any suitable means and from any desired location. Said movable valve 19 is 70 provided with two sets of ports 20 and 21 adapted to register respectively with the hot and cold inlet ports 17 of the shell 16 when the valve 19 is open. Figs. 2 and 4 show the valve 19 in closed position and 75 with the cylindrical surface of the valve closing the ports 17. The valve has a rim 22 which, in closed position, abuts against the right hand end of the shell 16. As a suitable means for manipulating the valve 80 19 automatically, we connect to it a neck or shank 23 carrying a piston 24 operating within the cylinder 25 at the left hand end of the main valve casing 13. The cylinder 25 is provided with ports 25^a and 25^b leading to the opposite ends thereof from a pilot valve chamber 26 in communication through a port 27 with the cold water chamber 18. 28 indicates a pilot valve slidable in said chamber 26 and adapted to control said 85 ports 25^a and 25^b. In the neutral position of the pilot valve, as shown in Fig. 2, both of said ports are closed.

90 At 29 we show a float disposed in a chamber 30 in communication with the water space of the washing machine, the position of the float being determined by the amount 95

of water in the machine. A link 31 is connected by means of an adjustable head 32 to a yoke 33, the adjustment being effected by means of a thumb nut 34. Said yoke is secured to a shaft 35 journaled in a bushing 36 at the front side of the wall of the cylinder 25, and the inner end of said shaft is bent upwardly at 35' and formed with a yoke 37 engaging the middle portion of said 5 valve 28. The yoke 33 in which the link 31 is adjustably connected extends laterally from the vertical plane of the shaft 35, and when said link is connected to the right hand end of the yoke, as shown in Fig. 7, the fall 10 of water level within the machine 10 will cause a corresponding drop of the float 29 and a movement of the yoke 33 and shaft 35 in a clockwise direction whereby the yoke 37 will move the pilot valve 28 toward the 15 right uncovering the port 25'. Water entering the chamber 26 from the cold water supply and passing through a port 28' of said pilot valve will enter the cylinder 25 and force the piston 24 and the valve 19 20 toward the right, bringing the ports 20 and 25 toward the right, bringing the ports 20 and 21 into registry with the inlet ports 17 and opening a series of outlet ports 38 into communication with the chamber 39 within the outermost shell of the main valve casing 25 25 which is in communication with the pipe 11 leading to the washing machine. It will thus appear that the desired level of water in the machine may be automatically maintained by means of the float connection with 30 the pilot valve 28. When the float 29 is lifted by the full supply of water within the machine, the valve 28 is returned to the position shown in Fig. 7, at which time water pressure enters the cylinder 25 through the port 25', forcing the piston toward the left 35 and shutting off the water by closing the ports 38. Upon setting the pilot valve 28 to its neutral position, as shown in Figs. 1 40 and 2, the valve 19 will remain closed. 45 Any suitable means may be used to cooperate with the movable valve 19 to determine the kind or character of water or the relative quantities of hot and cold water to be delivered to and mixed within the valve 50 casing. As a convenient and practical means for accomplishing this purpose, we provide a hollow cylindrical cut-off 39' fitted slidably within the shell of the valve 19 and operating between one series of inlet ports 20 and 55 the other 21. The cylindrical cut-off 39' may entirely close either of said sets of ports or may be adjusted so as to lie at any point between them, either leaving both sets open or leaving one open and the other partially 60 closed, it being understood, of course, that the open ports are made effective in any case only when they are in registry with the ports 17. The cut-off 39' has connected to it a stem 40 through a spider 41 at the inner 65 end, and said stem is connected to a hand

lever 42 adjustable along a segment 43 whereby the position of the cut-off is determined according to the temperature of the water desired. When adjusted to mid position, as shown in Fig. 7, both hot and cold water will be received when the valve 19 is open and delivered to the machine. If cold water only is desired, said cut-off 39' will be adjusted toward the right so as to close the ports 20 and 17 in communication with the hot water supply pipe 15. If hot water only is desired, the lever 42 will be adjusted toward the left, whereby the ports 21 and 17 pertaining to the cold water supply will be closed. As shown in dotted lines in Fig. 4, the cut-off is located so as to only partially close the cold water supply ports, and hence it will be understood that by providing a plurality of notches in the segment 43 any desired temperature may be secured for the water in the machine. The cut-off and its stem 40 operate within the valve 19 and independently thereof with respect to the adjustments or automatic operation hereinbefore described. 70 75 80 85 90 95 100

At 44 we show a drain pipe leading from the cylinder of the pilot valve and controlled by a pet cock 45. Among the objects of this drain is to provide for relieving the valve mechanism of water, which, when the machine is cold, might freeze therein; and also to allow any leakage to pass freely from the valve into the main discharge pipe. 105

Having thus described our invention, we claim as new and desire to secure by Letters Patent:—

1. In a device of the character set forth, the combination of a main casing having means to supply thereto different characters of fluid, a cylindrical shell within the casing, said shell having two series of circumferentially arranged inlet ports communicating with the several supply means, said supply means including circumferential chambers extending around and in communication with the respective ports, a cylindrical valve slidable within the shell and having two sets of ports adapted to register with the aforesaid ports, a cut-off slidable within the valve and adapted to close either series of ports aforesaid, and means to reciprocate said valve independently of the operation of the cut-off. 110 115

2. The herein described valve mechanism comprising a casing, a fixed shell within the casing, said shell being provided with spaced series of ports, a valve movable within the shell and having ports adapted to register with the aforesaid ports, means to deliver different characters of fluid to said shell and into communication with the several series of ports, a hand-controlled slidable cut-off 1

from the interior thereof the fluid received through said shell, substantially as set forth.

3. The herein described valve mechanism including a main casing having means to supply thereto different characters of fluids, a cylindrical shell within the casing, said shell having two series of circumferentially arranged inlet ports communicating with the several supply means, said supply means including circumferential chambers extending around and in communication with the respective ports, a cylindrical valve slideable within the shell and having two sets of ports adapted to register with the aforesaid ports, and means to reciprocate said valve so as to either open or close all of said ports.

4. The herein described valve mechanism including a main casing having means to supply thereto different characters of fluids, a cylindrical shell within the casing, said shell having two series of circumferentially arranged inlet ports communicating with the several supply means, said supply means including circumferential chambers extending around and in communication with the respective ports, a cylindrical valve slideable within the shell and having two sets of ports adapted to register with the aforesaid ports, a hand-controlled cut-off slideable within the valve and adapted to close either of said registering series of ports, and automatic means to reciprocate the valve independently of the movement of the cut-off, substantially as set forth.

5. The herein described valve mechanism for washing machines comprising a main casing having supply means for hot and cold water and an outlet for mixed hot and cold

water, each of said supply means including an annular chamber, a stationary cylindrical shell within said annular chambers, said shell having a series of ports communicating with each of said annular chambers and arranged throughout the extent of the annular chamber pertaining thereto whereby the water is delivered within the shell, a valve movable with respect to the shell on the inside thereof, and means controlled by the amount of water delivered for automatically moving said valve, substantially as set forth. 50

6. The herein described valve mechanism for washing machines comprising a main casing having inlet ports for hot and cold water and an outlet port, a fixed cylindrical shell within the casing and spaced from the outer wall thereof, said shell being provided with inlet ports to deliver the hot and cold water separately into the shell, and a hollow cylindrical valve slideable within the shell, said valve having inlet ports adapted to 60 register with the shell inlet ports and also having outlet ports adjacent one end, said valve serving in one position to exclude the water and in another position to deliver the water received from the inlet ports through said outlet ports to and through the space between the outer casing wall and said shell. 65

In testimony whereof we have signed our names to this specification in the presence of two subscribing witnesses.

WILLIAM H. PERKINS.
CARL A. LINDGREN.
